UNITED STATES PATENT OFFICE.

WILLIAM E. B. HASSELKUS, OF JAMAICA, NEW YORK, ASSIGNOR TO INTERNATIONAL MOTOR COMPANY, OF NEW YORK, N. Y., A CORPORATION OF DELAWARE.

SEAT.

Application filed June 4, 1926. Serial No. 113,649.

This invention relates to revoluble seats for vehicles, such as rail cars, and has for its object to afford a co-operation of seat and pedestal which shall maintain the seat locked against rotation or removal except when such movement is intended. Accordingly the seat is provided with a spindle extending downwardly into a pedestal and devices are provided which are actuated to loosen the spindle and remove an obstruction to the rotation or removal thereof. More particularly, a lever is fulcrumed in the base of the pedestal, one arm of which may be depressed by the foot to cause the other arm to raise the spindle slightly, the lever also carrying an upwardly extending arm adapted in locked position to enter one of diametrically disposed locking recesses formed in a plate carried with the spindle. The upwardly extending arm may also be formed with an enlarged portion overlying the plate to prevent accidental or unauthorized removal of the seat.

In order that the invention may be clearly understood and readily carried into effect the same will now be described more fully with reference to the accompanying drawings illustrating a preferred embodiment thereof, in which:

Figure 1 is a view showing, in front elevation and partly in section, a pedestal and so much of a seat as is necessary to show an understanding of the invention.

Figure 2 is a plan view showing the pedestal taken in the plane indicated by the line 2—2 in Figure 1 and looking in the direction of the arrows.

Figure 3 is a fragmentary view showing locking means for the seat on the pedestal, taken in the vertical plane indicated by the line 3—3 in Figure 1.

The seat *a* is mounted upon and rigidly secured to a downwardly depending spindle *b* journaled or rotatable in a cylindrical sleeve or bearing *c* secured against rotation in the cylindrical base member *d* forming a part of the pedestal *d'*. The seat is reversed, or in fact turned to face in any direction, by turning it, and with it, of course, the spindle on which it is carried, with reference to the pedestal. It is normally locked against rotation and, particularly after a weight has been supported thereby, the

spindle is frictionally held within the bearing sleeve. To overcome this friction and also to effect the unlocking of the seat, a foot pedal *e* is depressed, which being formed on a straight lever *e'* of the first order, fulcrumed between its ends on the pivot *d'* raises the arm *e''* against the action of spring *f* and causes the ball end *e'''* to bear against the spherical bearing surface *b'* at the bottom of the spindle *b* to raise the spindle within the bearing sleeve to break the frictional engagement and raise the flange *g* away from the flange *e'* and thereby lift the diametrically disposed tapered lugs *h*, *H* out of the diametrically disposed recesses *c²*, *C²*. Lever *e* is also formed with an arm *e⁴* extending upwardly through a slot *d³* in the pedestal and carrying a roller *e⁵* at its upper end which is adapted to enter one of diametrically disposed recesses *g', G'* and *C³* formed in the peripheral edges of the respective flanges *g* and *e'* when the lever is not depressed to further lock the flanges against relative displacement. When the lever is depressed, the arm *e⁴* is moved to the right, as viewed in Figure 1, carrying the roller *e⁵* out of the recesses *G', C³*. A slight turn of the seat will now move the lugs *h*, *H* out of register with the recesses *c²*, *C²* and the recess *G'* out of register with the roller. The foot may then be taken off the pedal and the arm will then move to the left under the influence of the spring *f* and cause the roller to bear against the periphery of the flange *g*. The seat may then continue to turn through 180°, the roller riding over the edge of the flange until the lugs are again in register with recesses, this time, the respective recesses which were before diametrically opposite to the lugs, and the opposite recess *g'* in the flange *g* in position to receive the roller. As the respective recesses come into position, the weight of the seat causes the flange *g* to approach flange *e'*, the tapered lugs *h*, *H* to drop into engagement in the recesses and the roller to enter the recesses *g', C³*. Extreme deflection of the pedal will move the arm *e⁴* outwardly far enough to cause the washer *e⁶* carried above the roller to clear the flange *g* and permit the complete removal of the spindle *b* out of the socket *c*; but in ordinary circumstances, when the roller is riding on the periphery of

the flange, the washer overlies that flange and prevents accidental separation of the seat and pedestal.

A revoluble seat has thus been provided which is locked against unintentional displacement or removal, but which is easily unlocked for rotation or removal by the depression of a foot pedal.

Various modifications in the configuration 10 of the component elements going to make up the revoluble seat and its locking devices as well as in the locking devices themselves will occur to those skilled in the art without departing from the spirit and scope of 15 the invention.

What I claim is:

1. A revoluble seat including a spindle, a pedestal formed with a socket to frictionally receive the spindle, a flange carried with 20 the spindle, a flange carried with the socket, said first named flange being formed with diametrically disposed peripheral recesses, diametrically disposed tapered lugs carried on the first named flange, said 25 second named flange being formed with diametrically disposed peripheral recesses to register with the first named recesses and with diametrically disposed recesses in the upper face thereof to receive the lugs, a lever 30 fulcrumed on the pedestal and having one arm formed as a foot pedal and with the end of the other arm disposed below the spindle, an upwardly extending arm carried by the lever, and a roller carried with the last named arm to enter the peripheral 35 recesses in the flanges.

2. A revoluble seat including a spindle,

a pedestal formed with a socket to frictionally receive the spindle, a flange carried with the spindle, a flange carried with the socket, said first named flange being formed with diametrically disposed peripheral recesses, diametrically disposed tapered lugs carried on the first named flange, said 40 second named flange being formed with diametrically disposed peripheral recesses to register with the first named recesses and with diametrically disposed recesses in the upper face thereof to receive the lugs, a lever fulcrumed on the pedestal and having one arm formed as a foot pedal and with the end of the other arm disposed below the spindle, a spring to press said arm 45 away from the spindle, an upwardly extending arm carried by the lever, a roller carried with the last named arm to enter the peripheral recesses in the flanges, and a washer carried with the roller to overlie the flanges.

3. A revoluble seat including a vertical spindle, a vertical pedestal formed with a 50 socket to receive the spindle, a flange carried with the spindle formed with diametrically disposed recesses, a flange carried with the pedestal cooperating with the first flange to carry the weight of the seat and formed with a recess to register with one of said first 55 named recesses, latching means carried with the pedestal, and means to separate the flanges to carry the weight of the seat and to release the latching means simultaneously. 70

This specification signed this 24th day of May A. D. 1926.

WILLIAM E. B. HASSELKUS.
